DOORLOCK

Henry G. Voight, New Haven, Conn., assignor to
Sargent & Company, New Haven, Conn., a corporation of Connecticut

Application October 27, 1933, Serial No. 695,448

7 Claims. (Cl. 70—16)

This invention relates to locks and more particularly to the so-called "unit type" locks whereby the entire lock unit is assembled before being mounted and is placed in an opening in the edge 5 of a door in assembled condition.

One objection to locks of this character has been that they are usually expensive, and as a result have been used almost entirely in connection with office or other public buildings where 10 heavy and expensive hardware is used.

One object of the present invention is the provision of a lock of this character which may be economically manufactured and at the same time be serviceable and efficient in operation.

Another object of the invention is the provision 15 of a so-called "unit type" lock which is relatively small in size whereby it may be mounted in a relatively small opening in a door so that it may be used in locks upon interior doors of dwellings or the like.

A still further object of the invention is the provision of a cheap and compact lock of the character set forth which will operate satisfactorily and which may be mounted in a relatively small 20 sized opening in the door, and which at the same time may be manufactured at a relatively low cost whereby it may have universal use.

To these and other ends, the invention consists in the novel features and combinations of 25 parts to be hereinafter described and claimed.

In the drawings:

Fig. 1 is an elevational view of the lock embodying my invention mounted upon a door;

Fig. 2 is a front edge view of the door and lock;

Fig. 3 is a sectional view through the lock case taken on line 3—3 of Fig. 2;

Fig. 4 is a transverse sectional view of the lock taken on line 4—4 of Fig. 1;

Fig. 5 is a plan view of the lock case with the cover and some of the parts removed;

Fig. 6 is an enlarged sectional view on line 6—6 of Fig. 3;

Fig. 7 is a plan view of the lock mechanism, a part of the cover being broken away to disclose the interior parts, and

Fig. 8 is a detail view of the dead bolt.

To illustrate a preferred embodiment of my invention, I have shown my improved lock as mounted upon a door 10. The lock comprises a case 11 having a cover 12 and a front plate or face plate 13. The case just described may be termed an interior case as it is concealed by escutcheon plates 14 and 15. One of the escutcheon plates, in this instance the plate 14 mounted upon the outside of the door, is secured directly to a

boss 16 on the lock case by the screw 17. The inner escutcheon plate 15 is secured by a screw 18 to a threaded boss 19 on the cover 12. It will be noted that the screw 18 and boss 19 are arranged to provide for considerable adjustment of the plate 15 toward and from the cover 12 of the inner case to allow for the lock being mounted upon doors of various thicknesses. The lock will be mounted with the escutcheon plate 14 adjacent the outer surface of the door, and the screw 18 will be threaded into the boss 19 until the escutcheon plate 15 fits closely upon the inside surface of the door.

The cover plate 12 is secured adjacent its front end to the lock case by means of the screw 20, shown more particularly in Fig. 6, and at its rear end is secured to the lock case by means of a U-shaped clip 21 which embraces the edge of the cover plate 12 and is held fast to the case by means of the screw 22. This U-shaped clip is provided with legs 23 and 24 which serve a function in addition to holding the cover to the case, as will be hereafter explained.

The lock mechanism consists of a latch bolt 25 having the usual beveled head 26, the bolt stem 25 at its rear end being provided with yoke arms 27 and 28 engaged by the opposite ends of a rollback 29 secured to, or formed integrally with, the hub 30. A spring 31 is mounted within a slot 32 in the bolt stem and reacts between a post 30 at its rear end and the head of the bolt to urge the bolt to protracted position. It will be noted that the latch bolt is mounted at the lower end of the lock, and the yoke arm 27 is considerably offset from the stem at the rear end of the case 35 to allow room above the stem and in the front end of the case for the dead bolt locking parts.

The knob hub 30, as shown more especially in Fig. 6, is what may be termed a floating hub, in that it has no bearing in the walls of the case as 40 in the usual lock construction at the present time. This enables me to make the case more compact and to manufacture it more economically. The hub is held in place by means of the spindle 34, which in this instance is square in 45 cross section and which passes through a square opening in the hub. The ends of this spindle are received in similarly shaped openings of the shanks 35 and 36, the shank 35 carrying the outside knob 37, and the shank 36 carrying either 50 a knob or the handle 38 as shown in Fig. 2.

It will be noted that the knob shanks 35 and 36 have relatively shallow bearings in the case and are provided at a point adjacent the exterior walls of the case with circumferential grooves 39 and 55

40. The legs 23 and 24 of the clip member 21 project into the grooves 39 and 40 to hold the knob shanks against longitudinal movement relatively to the case, as well as to hold the rear end of the 5 cover to the body of the case. It will be apparent that this construction provides a very simple and economical way of securing the knobs upon the case in suitable bearings which are formed integrally with the case parts, and at the same time 10 providing for the proper support of the hub in alignment with the knob shanks by having the hub carried by or supported by these shanks. It will be noted that the case is provided with the thickened parts or bosses 41 and 42 to provide the 15 bearings for the knob shanks.

The lock is also provided with a dead bolt 45 having a stem 46 projecting rearwardly into the case, the stem being provided with a slot 47 within which is received a guide post 48 secured to the 20 case. A tumbler 49 is pivoted on the post 48 and spring pressed downwardly, as shown in Fig. 7 by the spring 50.

The tumbler 49 is provided with a slot 51 into which projects a lug 52 on the tumbler, which 25 lug engages a post 53 formed on the bolt 45 to hold the bolt against accidental displacement from both retracted and protracted positions, as is well known in the art. Mounted below this tumbler in the case is a key hub or barrel 54 30 rotatably mounted in the sides of the lock case and provided with a key slot 55 into which the key 56 may be inserted. This hub is provided with a cut-away portion 57 through which the bit of the key projects to engage the tumbler 49 and 35 raise it upon the pivot 48 so that the post 53 is disengaged from the lug 52. The hub 54 is provided with wings or rollbacks 59 and 60 projecting from opposite sides thereof, the rollback 60 being adapted to move upwardly from the position 40 shown in Fig. 5 and engage the talons 61 on the dead bolt to move this bolt to protracted position.

Adjacent the wall of the case, a ward 62 is 45 slidably mounted between guides 63 and 64 on the case and is urged downwardly to the position shown in Fig. 5 by the spring 65. This ward is provided with spaced arms 66 and 67 having notches 68 and 69 to receive the rollbacks 59 and 60. It will be noted that the rollback 60 is slightly 50 longer than the rollback 59 so that the rollback 60 can never move downwardly past the lower edge of either of the notches. When this rollback is in the position shown in Fig. 5 the bolt 45 will 55 be in retracted position. When the key is inserted in the hub, any attempt to turn the key in a clockwise direction will be prevented by the engagement of the rollback with the lower corner of the notch 69. The key can be turned, however, in an anti-clockwise direction, as shown in 60 this figure, upon which movement the ward 62 will be moved upwardly against the tension of the spring and allow the rollback to move into engagement with the talons 61 of the bolt to move it to protracted position. The rollback will be 65 moved through an angle of 180 degrees until it rests in the notch 68, when further movement will be resisted by engagement with the lower corner of the notch 68. The reverse movement of the rollback will retract the bolt and restore the parts 70 to their original positions.

It will be noted that the head 79 of the screw 22 is conical in shape. When the lock is inserted into the opening in the edge of the door, this screw head may be driven into the wood 75 of the door to locate and prevent any move-

ment of the rear part of the lock. The case will be held in place otherwise by its connection to the two escutcheon plates, which are screwed to the door as shown at 72 in Fig. 1. These screws will enter the wood of the door rearwardly of the opening made for the lock case. 5

The operation of the lock will be clear from the foregoing description, and it will be apparent that the construction shown provides a compact and economically constructed door lock of the unit type having both latch and dead bolts, which lock may be mounted on a door with a minimum amount of labor. 10

While I have shown and described a preferred 15 embodiment of my invention, it will be understood that it is not to be limited to all of the details shown, but is capable of modification and variation within the spirit of the invention and within the scope of the appended claims. 20

What I claim is:

1. A door lock comprising a case having a detachable cover, a knob shank rotatably mounted in the case, and common means for securing the cover to the case and preventing longitudinal movement of the shank relatively to the case. 25

2. A door lock comprising a case having a detachable cover, a knob shank rotatably mounted in the case, and a member secured to the case and embracing the edge of the cover to hold the latter in position, said member engaging the knob shank to prevent longitudinal movement thereof. 30

3. A lock comprising a case, a lock bolt and operating mechanism therefor mounted in the case, a handle shank rotatably mounted at each side of the case, and a member secured to the end of the case and having end portions embracing the sides of the case, said end portions being engaged with said shanks to prevent longitudinal movement thereof. 35

4. A lock comprising a case, a lock bolt and operating mechanism therefor mounted in the case, a handle shank rotatably mounted at each side of the case, a member secured to the end of the case and having end portions embracing the sides of the case, said shanks being provided with peripheral grooves, and said end portions projecting into said grooves to prevent longitudinal movement of the shanks. 45

5. A lock comprising a case and a cover therefor, a member secured to the case and embracing the cover to hold the latter in position, means to secure said member to the case comprising a screw having a conical head projecting from the rear edge of the case, and the head of said screw being adapted to be engaged with the material of the door to hold the case in place. 55

6. In a door lock, a case, a latch bolt operatively mounted in the case, a knob shank at each side of the case, the ends of said shanks being rotatably mounted in bearings in the walls of the case, a hub within the case and disposed between the opposing ends of the knob shanks, means on said hub to actuate the latch bolt, a spindle non-rotatably secured within the hub and having its ends projecting therefrom, the projecting ends of said spindle being non-rotatably received in the ends of the knob shanks, and means secured to the case and engaging the knob shanks to prevent longitudinal movement of the latter relatively to the case. 65

7. In a door lock, a case, a latch bolt opera- 70

75

tively mounted in the case, a knob shank at each side of the case, the ends of said shanks being rotatably mounted in bearings in the walls of the case, a hub within the case and disposed between the opposing ends of the knob shanks, means on said hub to actuate the latch bolt, a spindle non-rotatably secured within the hub and having its ends projecting therefrom, the projecting ends of said spindle being non-ro-

5 tatably received in the ends of the knob shanks, each of said knob shanks being provided with a circumferential groove at the exterior of the case, and a member secured to the outside of the case and entering the groove of each knob shank to secure the latter against longitudinal movement relatively to the case. 5

HENRY G. VOIGHT.
